WASTE AND OVERFLOW FITTING

Abram N. Pasman, Waterbury, Conn.

Application November 25, 1930
Serial No. 497,984

11 Claims. (Cl. 285—29)

This invention relates to waste and overflow fittings such as are particularly adapted for use on bath tubs and the like. It is customary in making fittings of this type to employ a T member to which the overflow, waste and outlet pipes are connected. In this construction the overflow and outlet pipes are connected to oppositely disposed portions of the T member and are consequently maintained in vertical alignment. Because of the variations in the slope or inclination of the side walls of different fittings, the waste pipe connecting the waste outlet of the tub and the T member varies in length. This requires the use of a specially formed waste pipe connection, depending on the slope of the particular tub, and entails considerable difficulty in making the fitting.

The primary object of my invention, therefore, is the provision of a combined fitting whereby the use of a T member is obviated and to which the various connections are adapted to be made regardless of the slope of the sides of the tub.

In carrying out the invention I prefer to combine the waste pipe L, overflow L connection and discharge outlet connection into a single integral unit as will be hereinafter more particularly described.

A further object is to provide a fitting which is directly associated with the waste outlet and which may be utilized regardless of the pitch of the tub.

Another object is to provide a fitting which permits flexibility in assembling the various parts which are adapted to be connected thereon.

A further object is to provide an overflow L fitting or attachment which is adjustable and which is maintained against the side walls of the tub at any desired angle. The overflow pipe extending therefrom is readily connected to the combined fitting regardless of the pitch or slope of the tub.

Another object is the provision of a waste plug strainer in which the water outlet therethrough is considerably enlarged thereby permitting a more speedy emptying of the waste matter in the tub.

Another object is to provide a fitting of this type with one or more adjustable connections of novel construction which are associated with the said combined unit as will be hereinafter more particularly described.

My invention further includes other objects, advantages and novel features of design, construction and arrangement hereinafter more par-

ticularly referred to and which will be apparent from the accompanying drawings.

In which:

Fig. 1 is a sectional elevation illustrating the invention in association with a tub. 60

Fig. 2 is a side elevation showing one form of the combined fitting unit.

Fig. 3 is a front elevation of the ferrule or ring member showing the association between the same and the cross bar of the overflow L member. 65

Fig. 4 is a front elevation of the waste plug member.

Fig. 5 is an elevation of the member illustrated in Fig. 4. 70

Fig. 6 is a front elevation of the cross bar member.

Fig. 7 is a side elevation of the member shown in Fig. 6.

Fig. 8 is a front elevation showing a modification of the cross bar. 75

Fig. 9 is a rear elevation of a modified form of an overflow escutcheon.

Fig. 10 is a sectional elevation illustrating a modification in the form of the combined fitting. 80

Fig. 11 is a side elevation showing a further modification of the fitting, and

Fig. 12 is a plan of the fitting as illustrated in Fig. 11, a portion of the connection to the discharge pipe being illustrated in section. 85

Referring to the drawings, and particularly to Figures 1 and 2, the apparatus made in accordance with my invention includes a combined fitting for the discharge of waste fluid either directly from the waste outlet of the tub or indirectly from the overflow connection associated therewith. This combined fitting is indicated at 20 and integrally includes a waste L connection 21 directly associated with the waste outlet of the tub, an overflow L connection 22 and a discharge outlet 23. 90

While the invention as hereinafter described will be made to relate to plumbing for the release of waste water, it will be understood that the flow of other liquids may also be controlled by the use of a fitting made in accordance therewith. 100

The bath tub, or similar fixture, with which the invention is associated comprises a sloping side wall and a bottom wall as indicated at 24 and 25 respectively. The bottom wall 25 of the tub has the usual waste opening indicated at 26 in which a waste plug member 27 illustrated in Figs. 4 and 5 is located. The upper portion of 110

the member 27 is flanged as indicated at 28 to maintain the same in a fixed position in the opening 26 substantially coincident with the bottom portion of the tub. The lower portion of 5 the member 27 is threaded as indicated at 29 to engage a tapped opening 30 in the waste L portion of the fitting 20. A suitable washer 31 is interposed between the under surface of the tub and the waste L connection 21 of the fitting to 10 insure a water tight joint between these respective members.

Cross bars 32 and 33 are integrally associated with the lower portion of the member 27 to form a strainer therefor. The cross bars are arranged 15 substantially at right angles to one another and extend from the member 27 in the form of a basket. This construction increases the area available for the discharge of the waste water and consequently facilitates a speedier emptying 20 of the contents of the tub.

A circular rib 34 extends from the body portion of the fitting 20 and is internally threaded as indicated at 35 to receive an externally threaded fastening member or nut 36. The portion 25 of the casing 20 defining the discharge opening 23 is curved in a downwardly direction as indicated at 37, the lower surface of the same presenting a circular concave surface or seat 38 against which the curved upper portion of a 30 discharge pipe 39 is adapted to position. A gland ring member is indicated at 40, the purpose of which will be hereinafter more particularly described.

In making this connection the upper portion 35 of the discharge pipe 39 is manually worked into a flange, the pipe being of lead or similar ductile material to approximate the concave surface 38 of the member 20. On the tightening of the nut 36 the upper surface of the gland ring 40 presses against the under surface of the pipe flange and forces the same to position against the concave surface 38 as clearly indicated at 41. Due to the flexible characteristics of the lead pipe, a firm fitting of the same in the member 20 is assured in this manner even in the 45 event that the cooperating members are not perfectly aligned.

The overflow L of the combined fitting 20 is inclined at an angle slightly more than 90° with 50 the center line of the fitting 20. This permits a greater degree of flexibility in joining the overflow pipe 42 to the L portion 22 as will be hereinafter more particularly described. The upper portion of this fitting is screw threaded as indicated at 43 to receive an internally tapped nut 44. The interior walls are bevelled as indicated at 45 to seat a washer 46 between its surface and the exterior of the overflow pipe 42. The washer is preferably of lead or similar ductile 55 material so that the inner surface of the tapped nut 44 will force the washer to a tight fit against the bevelled surface of the fitting 20 when the nut is tightened.

In this construction the end of the overflow 60 pipe 42 extending into the fitting 20 is not rigidly maintained in alignment with the overflow L portion of the fitting. Regardless of the angle, which the pipe 42 may assume in the fitting 20, a tight connection is assured through the washer 46. A greater degree of flexibility is therefore obtained between these respective parts by having the overflow L connection of the fitting 20 pitched substantially at a corresponding angle to the average slope or inclination of the side 70 walls of a tub.

An overflow elbow connection 47 is threaded as indicated at 48 to maintain the tapped end of the overflow pipe 42 therein adjacent the tub. The elbow connection 47 comprises a bell shaped flange 49, the surface of which is adapted to engage a washer or gasket 50. In the interior of the elbow 47 are oppositely disposed recessed lugs, one of which is indicated at 51, the inner surfaces of the same being adapted to coact with the curved end surfaces of a cross bar 52, clearly illustrated in Figure 1. A flanged ferrule 53 is adapted to extend through the overflow outlet opening in the tub wall to maintain the washer 50 thereon. Bosses 54 and 54' extend from the ferrule and contain screw openings therein through which the screws 55 and 56 are placed to engage tapped openings 57 and 58 in the cross bar 52 illustrated in Figures 3, 6 and 7. When the retaining screws 55 and 56 are drawn tight the elbow 47 is firmly pressed against the washer 50 and connected to the tub wall, regardless of its pitch, the curved surface of the cross bar 52 adapting itself to position against the lugs to accommodate variations in the slope of the tub walls. The overflow opening is covered by the usual plate or escutcheon 59 secured in position by a center screw 60 in the tapped opening 61 of the cross bar 52. The customary chain and stopper associated with the tub fixture are indicated at 62 and 63 respectively.

Referring to Figures 8 and 9, modified forms of the cross bar and overflow plate are illustrated. The plate or guide for the overflow opening is constructed to include a circular recessed groove 64 adapted to coact with the outer surface of the ferrule 53. The cross bar has a single centrally tapped opening 65 for the reception of the screw 60. In this construction the elbow is secured to the tub by the use of a single central screw from the plate to the cross bar, the ferrule 66 being maintained in position against the plate and the washer against the bell shaped flange of the elbow. The cross bar adjusts itself within the oppositely disposed lugs in the elbow so that these respective members are fastened together without exerting any bending action on the screw. The connection of the various members associated with the elbow is easily facilitated regardless of the pitch or slope of the tub.

Referring to Figure 10 a modification of the 125 combined fitting is illustrated in relation to the waste outlet of the tub. The combined fitting unit is indicated at 66 and is directly associated with the waste plug member 67 substantially as hereinbefore described. The overflow L connection integral therewith is indicated at 68 into which an overflow pipe 69 extends and is adjustably maintained by a nut 70 and washer 71. A discharge connection of the fitting is indicated at 72 which in this instance is located in alignment 130 with the overflow L connection, it being particularly desired to emphasize that the position of the discharge outlet may be located at any desired point in the combined fitting without departing from the nature and spirit of the invention. A discharge pipe is indicated at 73 and is adjustably secured to the connection 72 by means of a nut 74 and washer 75.

Referring to Figures 11 and 12, the fitting is illustrated having a discharge connection located 145 at one side of the same as indicated at 76. Waste outlet and overflow L connections are indicated at 77 and 78 respectively.

The discharge connection 76 is internally threaded as indicated at 79 to receive a tapped 150

spud insert 80 having a circular concave face 81 extending outwardly therefrom, the upper portion being substantially flush with the end of the discharge connection 76. This connection is also 5 exteriorly threaded as indicated at 82 to receive an internally tapped fastening member or nut 83. A gland ring is indicated at 84. In a manner substantially similar to that hereinbefore described, the upper portion of a discharge pipe 10 85, which is of ductile or soft material such as lead, is manually worked into a flange approximating the concave surface of the spud insert 80. When the fastening member 83 is tightened on the outlet connection 76, the gland ring presses 15 against the under surface of the flanged pipe 85 and forces the same to position against the concave surface 81 of the spud insert. The pliable character of the lead pipe insures that a tight fit be made around the entire periphery of the 20 spud insert even in the event that the outlet connection 76 and discharge pipe 85 are not in perfect alignment.

The inventive concepts herein disclosed may be employed in other desired forms. Therefore, 25 various modifications of the present improvements may occur to those skilled in the art and may be made without departing from the scope and purview of the invention.

I claim as my invention:

30 1. In a fitting of the class described, in combination with a bath tub or the like having an overflow opening, a flanged ferrule in said opening with the flange abutting the side of the tub or, the like adjacent said opening, an overflow L 35 connection having oppositely disposed recessed lugs therein, means comprising a cross bar associated with said lugs for connecting said ferrule and said connection, whereby the connection is 40 adjustably maintained in relation to the side walls of the tub defining said opening.

2. In a fitting of the class described, in combination with a bath tub or the like having an overflow opening, a flanged ferrule in said opening with the flange abutting the side of the tub, 45 or the like adjacent said opening, an overflow L connection having a bell shaped flange at one end thereof, an overflow pipe adapted for positioning on the other end, oppositely disposed recessed lugs within said L connection, means 50 comprising a cross bar associated with said lugs and said ferrule whereby the bell shaped flange of the connection is adjustably maintained in relation to the side walls of the tub having said opening.

55 3. In a fitting of the class described, in combination with a bath tub or the like having an overflow opening therein, a ferrule extending through said opening, said ferrule having a flanged portion engaging one side of the tub wall defining the opening, a washer positioned on said ferrule adjacent the opposite side of the tub wall, an overflow L connection comprising a flange on one side thereof to engage said washer, an overflow pipe adapted for positioning on the other end, oppositely disposed recessed lugs within said L connection, an adjustable cross bar extending 60 between said lugs, connecting means between said ferrule and bar whereby said L connection is adjustably maintained in position against said washer.

70 4. In a fitting of the class described, in combination with a bath tub or the like, having an overflow opening therein, a ferrule extending through said opening, said ferrule having a flanged portion engaging one side of the tub wall

defining the opening, a washer positioned on said ferrule adjacent the opposite side of the tub wall, an overflow L connection comprising a flange on one side thereof to engage said washer, an overflow pipe adapted for positioning on the other end, oppositely disposed recessed lugs within said L connection, an adjustable cross bar extending between said ferrule and bar whereby said L connection is adjustably maintained in position against said washer, an overflow guard plate associated with said opening, and means for connecting the same to the adjustable cross bar. 80

5. In a fitting of the class described, in combination with a bath tub or the like having an overflow opening therein, a ferrule extending through said opening, said ferrule having a flanged portion engaging one side of the tub wall defining an opening, a washer positioned on said ferrule adjacent the opposite side of said tub wall, an overflow L connection having a flange on one end thereof to engage said washer, an overflow pipe adapted for positioning on the other end, oppositely disposed recessed lugs within said L connection, a cross bar extending between said lugs and adjustably maintained within said L connection, a guard plate having a circular recessed groove adapted to position against the flanged portion of the ferrule, and connecting means between the plate and cross bar whereby said L connection is adjustably maintained in position against said washer. 90

6. In combination with a tub or the like having an overflow opening, a flanged ferrule mounted in said opening, an overflow L connection provided with recessed lugs, and means including a cross-bar associated with said lugs for connecting said ferrule and said L connection to said tub or the like adjacent said opening. 100

7. In combination with a tub or the like having an overflow opening, a ferrule provided with projecting ears, said ferrule being mounted in said opening, an overflow L connection provided with lugs, and means associated with said ears and said lugs and including a cross-bar associated with said lugs for connecting said ferrule and said L connection to said tub or the like adjacent said opening. 110

8. In combination with a tub or the like having an overflow opening, a ferrule provided with projecting ears, said ferrule being mounted in said opening, an overflow L connection provided with lugs and means associated with said ears and lugs and including a cross-bar associated with said lugs for connecting said ferrule and said L connection adjacent said tub opening, said cross-bar having a curved bearing surface to provide means whereby the L connection may be adjustably connected to said tub or the like. 120

9. In a fitting of the class described, in combination with a tub or the like having an overflow opening therein, a ferrule extending through said opening, said ferrule having a flanged portion engaging one side of the tub wall adjacent said opening, an overflow L connection, a washer positioned between said L connection and one side of the tub wall, an overflow pipe associated with one end of said L connection, oppositely disposed lugs within said L connection, a cross-bar mounted in said lugs, said cross-bar being provided with a curved bearing surface so that the cross-bar is adjustably positioned with respect to said lugs, connecting means between said ferrule and said cross-bar whereby said L connection, 130

140

145

150

tion is adjustably maintained in position against the said washer.

10. In a combination of the character described, comprising a ferrule adapted to be mounted in an overflow opening of a tub or the like, said ferrule being provided with projecting ears, a tubular connection provided with lugs, a cross bar positioned in said lugs, and means associated with said ears and cross bar for connecting said ferrule and said connection.

11. In combination with a tub or the like having an opening, a flanged ring member extending through said opening and having the flange abutting the sides of the tub adjacent the opening, an overflow connection provided with recessed lugs and means including a cross bar associated with said lugs for connecting said flanged ring member and said connection to the tub or the like adjacent said opening.
